United States Patent Office.

BENJAMIN P. LAMASON, OF MILTON, PENNSYLVANIA.

Letters Patent No. 69,225, dated September 24, 1867.

IMPROVEMENT IN AXLE-BOXES.

The Schedule referred to in these Letters Patent and making part of the same.

TO ALL WHOM IT MAY CONCERN:

Be it known that I, BENJAMIN P. LAMASON, of Milton, in the county of Northumberland, and in the State of Pennsylvania, have invented a new and useful Improvement on Caps or Lids for Railroad Car Boxes; and I do hereby declare that the following is a full, clear, and exact description of the construction and operation of the same, reference being had to the annexed drawings, making a part of these specifications, in which—

Figure 1 is a front view of cap showing form, &c.

Figure 2, a transverse section through *a a*, showing hook or clamp *b* and stop *f*.

Figure 3 is a longitudinal section through *b b*, showing cap *A* and car-box *B*, the mode of attaching the cap to box, and also the operation of hook or clamp *b*.

Figure 4 represents a part of car-box, with a portion of cap showing the position of cap when properly adjusted.

To enable others skilled in the art to make and use my invention, I will proceed to describe its construction and operation.

I construct my cap in the form of an elliptic, of cast iron, brass, or any like metal. I make a hole in one end of cap *a*, fig. 1, and on the other end I construct a hook or clamp, *b*, figs. 2, 3, and 4. This hook or clamp *b* is so constructed and arranged as to fit around the box-car *d*, figs. 3 and 4. The car-box being constructed of the usual form, the cap *A* is secured to car-box *B* by means of the bolt or screw *c*, passing through the cap at the hole *a*, and screwed into the box-car *d*, thus forming a secure and efficient attachment. The bolt *c* also forms a pivot, on which the cap *A* revolves. The other end of cap is secured by means of the hook or clamp *b* passing around and back of box-car *d*, shown at *e*, fig. 3. This simple device, it will be readily seen, forms a secure fastening when cap is in place.

I operate the cap by means of the hands, the one end of cap being permanently secured to box by the bolt *c*. The other end on which hook or clamp *b* is constructed, is left free, and can be raised up or lowered down, as the desire may be, to open or close the box. The stop *f*, fig. 2, is designed to prevent cap from dropping too low when cap is closed.

The advantages claimed for my improvement are, first, it obviates the necessity of using more than one bolt; second, is readily applied to new or old car-boxes, and is easily operated, no tool or instrument being necessary; third, it is permanently secured to car-box, thus preventing the loss of cap and bolts.

What I claim as my invention, and desire to secure by Letters Patent, is—

The car-axle box lid *A* provided with the clamp *b*, in combination with the car *d*, applied to the car-axle box.

BENJ. P. LAMASON.
